J. TURNER.
COMBING MACHINE OF THE NASMITH TYPE FOR COMBING COTTON OR OTHER TEXTILE FIBERS.
APPLICATION FILED JAN. 19, 1920.

1,379,789.

Patented May 31, 1921

FIG. 1.

FIG. 2.

INVENTOR:
Joseph Turner
By Wm Wallace White
ATTY.

UNITED STATES PATENT OFFICE.

JOSEPH TURNER, OF MANCHESTER, ENGLAND.

COMBING-MACHINE OF THE NASMITH TYPE FOR COMBING COTTON OR OTHER TEXTILE FIBERS.

1,379,789.

Specification of Letters Patent. Patented May 31, 1921.

Application filed January 19, 1920. Serial No. 352,490.

To all whom it may concern:

Be it known that I, JOSEPH TURNER, a subject of the King of Great Britain, residing at Sedgley Park, Prestwich, Manchester, in the county of Lancaster, England, have invented new and useful Improvements in Combing-Machines of the Nasmith Type for Combing Cotton or other Textile Fibers, of which the following is a specification.

10 In the Nasmith combing machine as at present constructed the cam shaft is coupled up to the shaft upon which the needle segments are securely fixed and extends the whole length of the machine, the result being that the nippers which hold the cotton to the needles while combing arrive too late at the most effective position and generally allow about 6 rows of the front needles to pass before any combing action takes place; 15 consequently the burden of the work in opening out the tangled mass of fibers held by the nippers devolves on the finer needles which suffer through not being able to withstand the strain and the machine itself loses 20 a valuable part of its combing capabilities. This defect is well known and various inventors have accelerated the speed of the nippers in the Nasmith type of comber so as to arrive in time for the earlier or front rows 25 of needles but as this gives rise to greater vibration of the machine it is objectionable.

In the Heilmann type of comber this defect has been obviated by applying a combination of elliptical or eccentric gears or 30 the like in order to impart a variable speed to the needle segments and my present invention consists essentially in the arrangement and application in a Nasmith type of comber of any suitable mechanism for imparting a variable speed to the needle segments for the purposes above indicated thus 35 allowing the front or any line of needles to become effective at any desired period.

To accomplish this object in the Nasmith 40 type of comber I separate the direct connection between the cam shaft and the shaft on which the needle segments are fixed and drive the latter at a variable angular speed, that makes one revolution for 45 each revolution of the cam shaft, by any known mechanical system of eccentric or elliptical gears or cam or cams or the like

and I drive the rollers in the drawing head from the needle or cylinder shaft at the usual constant speed or angular velocity. 55

I illustrate an embodiment of my invention in the accompanying sheet of drawings, in which—

Figure 1 shows the arrangement of elliptical gears introduced between the cam shaft 60 and the cylinder shaft and Fig. 2 shows an arrangement of gearing for counteracting the variable speed imparted to the cylinder shaft to insure that the drawing head is driven at the ordinary constant speed. 65

Referring first to Fig. 1, *a* designates the cam shaft to which is fixed the spur wheel *b* by means of the set screw as shown; this gears into a spur wheel *c* on the boss of which is fixed an elliptical wheel *d* which 70 gears into an elliptical wheel *e* fixed on the cylinder shaft *f*, on which is fixed the needle segments.

It will be seen that as the cam shaft *a* runs at a constant speed the cylinders or 75 needle segments will run at a constantly varying speed in order to obviate the defects above indicated and which have hitherto existed in combing machines of the Nasmith type. 80

Referring to the device shown in Fig. 2 it will be obvious that as a variable speed is imparted to the cylinder shaft *f* by means of the gearing described with reference to Fig. 1 or any suitable equivalent arrangement that unless some provision be made to counteract the same the drawing head will also be driven at a variable instead of the usual constant speed. Such counteracting device is shown in Fig. 2 and is introduced 85 in a suitable position between the cylinder shaft *f* and the shaft *n* driving the rollers on the drawing head of the machine. On the cylinder shaft *f* is fixed a bevel wheel *g* gearing into a bevel wheel *h* which is secured on the boss *i* of a spur wheel *j* and drives a spur wheel *k* on the boss of which is securely fixed an elliptical wheel *l*. This wheel *l* drives a second elliptical wheel *m* which is fixed by a set screw on the cross shaft *n* which rotates loosely in the boss of the wheel *j* which is supported by a bracket *o*. The other end of the cross shaft *n* drives the rollers of the drawing head in the usual 90 95 100

manner. The stud *q* Fig. 1 and stud *p* Fig. 2 are for the compound carrier wheels and may be fixed to any suitable bracket.

What I claim as my invention and desire 5 to secure by Letters Patent of the United States is:—

1. In a combing machine of the Nasmith type, a cam shaft, a needle shaft separated from said cam shaft, a drawing head roller shaft, means for imparting rotary motion 10 at a constant speed to said cam shaft, means between said cam and needle shafts for transmitting motion to the latter at variable speed, and means between said needle shaft 15 and drawing head roller shaft for transmitting motion to the latter at a constant speed.

2. In a combing machine of the Nasmith type, a cam shaft, a needle shaft separated from said cam shaft, a drawing head roller shaft, means for imparting rotary motion 20 at a constant speed to said cam shaft, a pair of elliptical gears between said cam and needle shafts for transmitting motion to the latter at variable speed, and a pair of elliptical gears between said needle shaft and drawing head roller shaft for transmitting motion to the latter at a constant speed. 25

In testimony whereof I have signed my name to this specification.

JOSEPH TURNER.
